JABEZ JENKINS, OF PHILADELPHIA, PENNSYLVANIA.

Letters Patent No. 92,532, dated July 13, 1869.

IMPROVEMENT IN HATCHET.

The Schedule referred to in these Letters Patent and making part of the same.

To all whom it may concern:

Be it known that I, JABEZ JENKINS, of Philadelphia, in the county of Philadelphia, and State of Pennsylvania, have invented a new and improved Hatchet; and I do hereby declare that the following is a full, clear, and exact description thereof, which will enable others skilled in the art to make and use the same, reference being had to the accompanying drawing, forming a part of this specification.

The present invention relates to a new and useful improvement in the construction of hatchets as a new article of manufacture, the blade or cutting-portion of the said hatchet being made of sheet-steel, and the poll of cast-iron, the construction of which will be understood from the following description.

Similar letters of reference indicate corresponding parts.

In this case, the letter A represents the blade of the hatchet. The said blade is stamped out of sheet-steel, and has one or more holes or slots, B, punched through its upper edge. The blade is then set in the mould, and molten iron or other metal is then poured into the said mould, which forms the poll or head of the hatchet.

It will thus be seen that the blade and poll, being securely connected by the molten metal running through the hole or slot in the plate, forming a solid rivet, will produce a good and neat hatchet at a greatly reduced price.

Having thus described my invention,

What I claim as new, and desire to secure by Letters Patent, is—

The hatchet, when constructed as herein shown and described, as a new article of manufacture.

JABEZ JENKINS.
